UNITED STATES PATENT OFFICE.

JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

NEEDLE MECHANISM.

Original application filed June 28, 1921, Serial No. 481,032. Divided and this application filed December 1, 1925. Serial No. 72,427.

This invention relates to sewing machines, more particularly to the needle mechanism thereof, an object thereof being to provide an improved needle mechanism having improved means for imparting to the needles a zig-zag movement and improved means for guiding and controlling the thread to such needles. 5

A further object of this invention is the provision of a sewing machine having improved means for vibrating the needle mechanism and in which the construction is such that the driving means therefor may be utilized for operating a cross stitch mechanism 15 for laying a thread in the path of the needles on top of the work; the present application being a division of my co-pending application filed June 28, 1921, Serial No. 481,032.

Other objects of this invention will appear in the following description and appended claims thereof, reference being had to the accompanying drawings forming a part of this specification, wherein like reference characters indicate corresponding parts 25 in the several views and wherein Fig. 1 is a front perspective view of the sewing machine with the transmitter and treadle connected for operating the same; Fig. 2 is an end view of the needle bar operating mechanism, portions of the needle bar bushings, oil cup and needle bar being broken away to clearly show the construction, and a portion of the overhanging arm and crank shaft shown in broken lines; Fig. 3 is a sectional view of 30 the rotary top stitch forming mechanism, the machine frame and cylinder being shown in broken lines; Fig. 4 is an end view of the mechanism shown in Fig. 3, the crank shaft and the frame of the machine being indicated in broken lines; Fig. 5 is a sectional view 35 of the presser foot and stitch mechanism carried thereby, taken on lines 5—5 of Fig. 3 looking in the direction of the arrows; Fig. 6 is a sectional view of the presser foot and stitch forming mechanism carried thereby taken on lines 6—6 of Fig. 4; Fig. 7 is a side elevation partly in section of the needle vibrating mechanism for making zig-zag stitches, the needle bar being shown 45 as pivotally mounted in the head of the machine for swinging, angular, and reciprocating 50 movement, the frame and cylinder being indicated in broken lines; Fig. 8 is an end view of the mechanism shown in Fig. 7, the crank shaft and frame of the machine being indicated in broken lines; Fig. 9 is an end view of the mechanism for imparting zig-zag movements to the needle bar at right angles to its line of vertical reciprocation, and Fig. 10 is a side view of a part of the machine. 55

Before explaining in detail the present improvement and mode of operation thereof, it is desired to have it understood that the invention is not limited to the details of construction and arrangement of parts which are illustrated in the accompanying drawings, since the invention is capable of other embodiments, and that the phraseology which is employed is for the purpose of description and not of limitation. 65

The present machine is mounted upon a suitable table 1 and comprises a machine frame of any suitable construction having flanges 2 and 3 for supporting and securing the machine to the table. The main portion of the frame is preferably of hollow rectangular construction and the front wall 4 of the frame is provided with a boss 11 bored to receive a cylinder 12. This cylinder 12 has a detachable end cap 343 and this cylinder carries the looper mechanism and feed bar, one of the loopers being indicated at 312. The side wall 13 of the frame is provided with a boss 14 for receiving one of the crank shaft bushings 15, the opposite side wall having secured thereto a suitable belt guard 22 which covers the driving belt 23. Mounted in suitable bearings of the frame is a transversely extending crank shaft 62, 63. This crank shaft is provided with a clutch wheel 93 located adjacent to the cover plate 22 over which passes the belt 23 of the transmitter. The power transmitter for the machine is designated generally 95 at A and is secured to the bottom of the table 1. The power transmitter is driven from any suitable line shaft, and comprises suitable clutch mechanism controlled from a floor treadle 159. A further detailed description of the power transmitter mechanism and the crank shaft mechanism is not 100

deemed necessary herein since the same is fully described in my above mentioned pending application.

Projecting from the front wall 4 is an overhanging arm 32 terminating in the needle bar and presser foot bearing 33. This overhanging arm 32 is provided with suitable bearings 37 and 38 for the needle operating rock shaft 39. Secured to the forward end of the rock shaft 39 by screws 40 is a needle bar operating arm 41. The end of the shaft 39 is tapped to receive a screw 42 and a thrust washer 43 thereby to prevent end movement of the arm 41 on the shaft 39.

At the outer end of the arm 41 by means of a joint pin 44 is secured a link 45, the bottom end thereof being connected by means of a joint pin 46 to an end piece 47 tapped into the needle bar 48 and clamped with a lock nut 49. The needle bar is hollow and the lower end is tapped to receive the needle holder 50 which carries the needles 51. The needle bar is provided with two openings 52, the upper one being an inlet and the lower one an outlet for oil for the purpose of internally oiling the upper and lower needle bar bushings, 53 and 54.

Secured to the top of the upper bushing 54 is an oil cup 55 provided with a felt oiler, carrying sufficient lubricant for the needle bar, but preventing the oil from dripping and soiling the goods. An intermediate felt oiler 56 is provided between the two bushings. These felt oilers wipe the needle bar in its reciprocating movement, keeping it clean and properly lubricated.

To the rear end of the rock shaft 39, adjacent to the bearing 37 is secured a crank arm 57 and ball stud 58, to which is connected the upper end of a ball connection 59. The lower end 60 also has a ball socket to fit over the ball 61 of the crank shaft.

The cross stitch mechanism for laying a thread in the path of the needles on top of the work, in alternating loop form is an improvement over the mechanism described in my Patent Number 1,464,377 dated August 7, 1923, for sewing machines. In the present machine however improved mechanism for driving the gears in the presser foot is provided over my aforesaid patent, and the presser foot is hinged to yield from front to rear in the direction of the feed of the goods in order to ride more freely over seams and uneven thicknesses of work.

Referring particularly to Figs. 3 to 6 inclusive, the mechanism comprises a driving gear 483 carried by the crank shaft. This driving gear meshes with a similar gear 484 of equal diameter secured to a shaft 485 by screws 486. These gears are located within the machine frame and the shaft 485 is given a rotary movement thereby. The shaft is supported in the rear bearing 487 and in the forward bearing 488, the bearings being se-

cured in a horizontal tube 489 cast in the L-shape section 32 of the machine frame. A hole is thus left for the shaft thereby saving the expense of drilling the same. To make the hole in the casting with a sand core was found impracticable. But by casting the metal around the steel tubing as in the present instance the cost is greatly reduced, the overhanging arm is strengthened, and it is merely necessary to enlarge each end of the tube in order to insert the bearings 487 and 488 for the shaft. This construction has the advantage of reducing the friction of the shaft and provides adequate space 490 for lubricant, which is supplied automatically, to pass from one bearing to the other. The forward end of the shaft carries a thread controller 491 adjustably secured thereto by the screw 492. The thread controller operates on the top thread as it is conducted from the supply to the presser foot and is fully described in my aforesaid patent.

Adjacent to the forward end of the bearing 488 is located a gear 493 secured to the shaft 485 by screws 494. This gear is in mesh with a gear 495 of equal diameter secured by screws 496 to the upper end of a vertical rotary operating shaft 497 for the rotary cross thread mechanism. This shaft is located in the hollow or tubular presser bar 183 and has a bearing 498 in the upper end of the tube or bar 183 and a bearing 499 in the lower end of the tube. Intermediate these bearings the shaft is reduced in diameter as at 500 to increase the flexibility of the shaft and to reduce friction. The presser bar or tube reciprocates vertically in the bushing 187 and is controlled by guides 185 and 186. The lower end 502 of the presser tube 183 is counterbored vertically at 503 to receive a coil spring 501. The top portion of the coil spring rests against the shoulder formed by the counterbore and the lower end rests against a flange 504 formed as a part of the shaft 497. Projecting from the flange is a semi-circular key 505 which fits into a semi-circular key hole provided in a gear 506 in mesh with an intermediate gear 507 rotating on the stem 508 of the screw 509. The intermediate gear 507 is in mesh with and drives a ring gear 511 which carries a rotary circular plate 512 provided with up-standing thread carrying lugs 513 for forming loops in the top thread. Co-acting with the lugs is a cast-off 514, integral with the ring 515. The ring gear 511 rotates in a socket in the presser foot, and the overhanging head 510 of the screw 509 impinges upon the flange of the ring 515 to hold the ring gear in position. This screw also acts as a pivot for the intermediate gear and as a locking means for the bottom 517, provided with beveled edges fitting into the presser foot 516, the stem 508 entering the hole 518 in the bottom 517. Thus the rotary cross thread

120
125
130

carrier 512 having its axis substantially aligned with the axis of the needle bar is provided with projecting lugs 513 movable in a continuous, circular, or rotary path around the needles. These lugs are adapted to engage the thread from the thread guide 526 (hereinafter described) and carry the same to a loop forming position, the cast-off member 514 being effective at the desired times to cast off the thread from the loop forming lugs.

The presser foot 516 is hinged to a yoke holder 522 by shoulder screws 521, one arm of the yoke being connected at 519 and the other arm at 520 to the sides of the presser foot, enabling the presser foot to rock slightly on the screws. Each of the arms has an overhanging shoulder 523 to contact with and limit the rocking movement of the presser foot. The yoke 522 is clamped to the presser tube or bar 183 by a screw 524 passing through the slotted rear walls, a space 525 permitting the heel of the foot to rise slightly when passing over seams. An eye 526 formed in one of the arms of the presser foot yoke guides the top thread into position for stitching formation, the same being preferably located to one side and slightly to the rear of a needle.

The object of the spring 501 acting between the shoulder 503 and the flange 504 is to give a slight downward pressure to the shaft 497 and hold the gear 495 in proper relation with the gear 493 to yield downwardly when a seam is passing under the toe of the presser foot, and to yield upwardly when a seam is passing under the heel of the foot. A more detailed description of the rotary cross stitch forming mechanism carried by the presser foot is deemed unnecessary since the same is fully described in my aforesaid Patent No. 1,464,877 dated August 7, 1923.

This cross stitch driving mechanism is also useful for operating a trimmer, top feed, ruffler, or other attachments and in the present improvement it is utilized for operating a zig-zag needle.

The zig-zag stitching mechanism cooperates with the looper mechanism, two forms of vibrating needle mechanisms being herein shown, one thereof swinging on a horizontal center located approximately mid-way between the ends of the needle bar, so as to swing upon the center to space the stitches as desired, the other comprising a right angle slide adapted to vibrate the needle and needle bar at right angles to the direction of the reciprocation. For certain classes of work the right angle movement is superior to the swinging movement, the swinging movement however being capable of a higher speed and therefor superior for light materials where a narrow vibration or bight of stitch is suitable.

Referring to Figs. 7 to 9 inclusive, in order to vibrate the needle the same gearing construction as shown and described in connection with the cross thread laying mechanism may be employed except that the gear 484 would have twice as many teeth as the gear 483, to give a two-to-one reduction to the shaft 485. That is to say the shaft would operate at half the speed of the crank shaft of the machine. At the forward end of the shaft 485 is located a triangular cam 527 secured to the shaft by screws 528 passing through the flange 529 of the cam. This cam operates in a fork 530 which straddles the cam, the fork being carried by the arm 531 which extends downwardly and is secured at 532 by screws 533 to the boss 534 of the swinging bearing 535. The swinging bearing 535 is bored to receive the lower and upper bushings 53 and 54 (Fig. 2) for guiding the needle bar 48, and has a tapered circular disc 536 integral therewith which is seated in a circular socket 537 formed in the face 538 of the head 33 of the machine frame. One-half of the circular socket is formed with a beveled circular plate 539 secured by screws 540, so that the swinging bearing may rock therein and be secured against shake or lost motion.

The second form of mechanism for vibrating the needle above mentioned comprises a shoulder screw 541 and a block 542 supported by it and operating in an elongated slot 543 of the arm 531. The lower end of the arm carries a shoulder screw 544 to which is connected the arm 545 of the right angle dove-tailed slide 546. The slide is integral with a needle bar bearing 547 carrying the bushings 53 and 54 for guiding the needle bar. This dove-tailed slide 546 is guided by a beveled edge plate 548 which is secured by screws 549 to the wall 538 of the end bearing 33 of the machine frame. The right angle slide construction permits the needle bar to be shifted laterally while it reciprocates in a vertical plane. The link connection 45 with its joint pins 44 and 46 permits either right angle movement or swinging movement as the case may be. The extent of the movement of the needle bar may be varied by substituting cams 527 of different throws. From the foregoing it will be seen that I have produced a very simple mechanism for making ornamental stitches of zig-zag form by giving right line or angular movements to a reciprocating needle bar and at the same time a portion of the operating means may be used to equal advantage for operating an ornamental cross thread stitch forming mechanism.

For the top needle thread control a bracket 409 is attached to the top of the cover plate 7, Fig. 1, which carries suitable tensions 410, three in number, and the usual nut and spring 411 for regulating the

tension on the threads. A pin 412 carried by the bracket 409 extends into a U-shaped opening in the bottom of the tension plates to prevent their turning on the center studs 411^a, while the upper ends have a pin 413 carried by one of the outside plates and extending freely through the intermediate plate and the usual outside plate, permitting the plates to be separated for inserting the 10 threads between them. The object of this pin 413 is to prevent the threads from being withdrawn from between the plates when they are drawn upward for the purpose of providing slack thread at the end 15 of each stitching operation. The threads 414 are conducted from the supply through the guide eyes 415 of the bracket 409 in between the two outside and intermediate tension plates 410, and through the guide eyes 20 416 in the right-angled bent end 206 of the thread pull-off lever 205. Thence they are conducted through the guide eyes 418 of a stationary eyelet also secured to the bracket 409 adjacent to the guide plates 207, which 25 straddles the free end of the lever 205 to guide it in its movements.

A thread guide 417 is attached at its forward end to an angle bracket 419 secured to the top portion of the frame. The threads 30 enter eyelets in the end 420 of the thread guide 417 which is slotted forming troughs for the threads throughout its length, except for the thread holes 421 at the forward end from which the threads emerge and are 35 led to thread eyes 422 of a thread carrier 423 carried by the end 424 of the link pin 46. From the thread eyes 422 the threads pass downward in through the eyes of the needles 51.

As a result of this mechanism for controlling and guiding the top thread from the supply to the needles an almost perfect control is obtained, and at no time during the 40 stitch forming cycle or movement of the parts does the thread become slack or out of control. The relation of the guide eyelets with the end of the trough shaped thread guide 417 is such that the threads are entirely protected by passing through the 45 thread trough guide from the thread eyes at 420 to the thread eyes at 421. The space from the thread eyes at 421 to the thread eyes at 422 permits a slight take-up action to the thread, which is desirable due to the 50 fact that the thread carrier 423 is reciprocated with the needle bar, the thread eyes 422 thus having a reciprocatory movement relative to the stationary thread eyelets 421. One advantage of the trough shaped thread 55 guide 417, extending lengthwise of the arm 32 of the machine frame, resides in the fact that it enables the operator to place articles that are being stitched or have been stitched, such as shoe uppers and the like, up over the 60 head 33 and permit them to rest on the arm

32 until the arm is completely filled with such articles while other work or articles may be passed over the cylinder 12 until that becomes filled. All the articles may then be removed from the cylinder 12 and the 70 arm 32 at the same time, thus reducing to a minimum the frequency of lifting the presser foot and breaking the stitches extending from one piece to another. As a result the machine may be kept in more continuous operation, one piece of goods being stitched directly after another, and without stopping the machine until a large number of pieces have been completed. Thereupon by raising the presser foot and so breaking the threads, all of the work may be removed at one time. The overhanging arm 75 32 and the head 33 are so constructed that very small articles may be passed over these parts, as well as over the cylinder 12. Another advantage of this construction is that the line of vision of the operator is not obstructed, permitting the inspection of the work immediately as it feeds from under the presser foot, during the operation of the 80 machine.

It is to be understood that by describing in detail herein any particular form, structure or arrangement, it is not intended to limit the invention beyond the terms of the 85 several claims or the requirements of the prior art.

Having thus explained the nature of my 90 said invention and described a way of constructing and using the same, although without attempting to set forth all of the forms in which it may be made, or all of the modes of its use, I claim:

1. In a sewing machine, the combination 95 of a machine frame having an overhanging arm, a pair of shafts carried thereby, one a rock shaft and the other a rotary shaft, means including a crank shaft located transversely to said shafts for driving said shafts, a needle carrying bar connected with the 100 rock shaft, and means for vibrating the needle bar and connected with said rotary shaft.

2. In a sewing machine, the combination 105 of a machine frame having an overhanging arm, a pair of shafts of substantially the same length carried thereby and projecting beyond the ends of said arm one a rock shaft and the other a rotary shaft, means including a crank shaft located transversely 110 to said shafts for driving said shafts, a needle carrying bar connected with the rock shaft, means for vibrating the needle bar and connected with said rotary shaft, and means for guiding the thread to the needle 115 and comprising a trough shaped member located on top of and extending from substantially one end to the other of said arm.

3. In a sewing machine, the combination 120 of a machine frame having an overhanging

arm, a pair of shafts of substantially the same length carried thereby lengthwise thereof, and projecting beyond the ends of said arm, means including a crank shaft located transversely to said shafts for driving said shafts, a needle carrying bar connected with one of said shafts, and camming means controlled by the other of said pair of shafts at the forward end thereof and cooperating with said needle bar for vibrating the same.

4. In a sewing machine, the combination of a machine frame having an overhanging arm, a pair of shafts carried thereby, one a rock shaft, means including a crank shaft located transversely to said shafts for driving said shafts, a needle carrying bar connected with the rock shaft, and camming means controlled by the other of said pair of shafts and cooperating with said needle bar for vibrating the same, said camming means including means pivotally located intermediate the ends of the needle bar to insure the proper spacing of the stitches.

5. In a sewing machine having an overhanging arm, the combination of a shaft carried by and extending lengthwise of said arm, means for driving said shaft, a needle carrying bar, means for reciprocating said bar and camming means located at the end of said shaft and cooperating with said needle bar for vibrating the same.

6. In a sewing machine having an overhanging arm, the combination of a shaft carried by and extending lengthwise of said arm, means for driving said shaft, a needle carrying bar, means for reciprocating said needle bar and camming means carried by said shaft and cooperating with said needle bar for vibrating the same, said camming means including means located intermediate the ends of the needle bar for swinging the same to space the stitches.

7. In a sewing machine having an overhanging arm, the combination of a shaft carried by and extending lengthwise of said arm, means for driving said shaft, a needle carrying bar, means for reciprocating said bar, a cam carried adjacent to the front end of said shaft and means cooperating with said cam and including a swinging member connected to said needle bar for vibrating the same.

8. In a sewing machine having an overhanging arm, the combination of a drive shaft, a shaft carried by said arm, a presser foot bar and a presser foot supported thereby, a rock shaft carried by said arm and operated from said drive shaft, a needle carrying bar connected to said rock shaft for reciprocating movement, and camming means carried by said second shaft and cooperating with said needle bar for vibrating the same.

9. In a sewing machine having an overhanging arm, the combination of a needle carrying bar, means for reciprocating said

needle bar, a rotary shaft carried in and extending lengthwise of said arm, means for rotating said shaft, and camming means carried at the forward end of said shaft and connected with said needle bar for vibrating the same.

10. In a sewing machine having an overhanging arm, the combination of a pair of shafts, one a rotary shaft and the other a rock shaft carried by and extending lengthwise of said arm, a crank shaft in proximity to the end of said rock shaft for operating said rock shaft, an oscillating arm connected to said rock shaft, a needle bar connected to said oscillating arm and reciprocated thereby, and means connected to the rotary shaft for laterally shifting said needle bar.

11. In a sewing machine having an overhanging arm, the combination of a pair of shafts, one a rotary shaft and the other a rock shaft carried by and extending lengthwise of said arm, a crank shaft at right angles and in proximity to the end of said rock shaft for operating said rock shaft, an oscillating arm connected to said rock shaft, a needle bar connected to said oscillating arm and reciprocated thereby, and means including a cam carried by the rotary shaft for laterally shifting said needle bar.

12. In a sewing machine, the combination of a drive shaft, a rock shaft operated thereby, an oscillating arm connected to said rock shaft, a reciprocating needle bar, a link pivotally connecting said oscillating arm and needle bar and effective to permit either a movement at right angles to the path of reciprocation of the needle bar or a swinging movement to the needle bar, and means for vibrating the needle bar and including an overhanging rotary shaft and means operated by said overhanging rotary shaft and connected with the needle bar.

13. In a sewing machine, the combination of a drive shaft, a rock shaft operated thereby, an oscillating arm connected to said rock shaft, a reciprocating needle bar, a link pivotally connecting said oscillating arm and needle bar and effective to permit either a movement at right angles to the path of reciprocation of the needle bar or a swinging movement to the needle bar, and means for vibrating the needle bar and including an overhanging rotary shaft and camming means operated by said overhanging rotary shaft and connected with the needle bar.

14. In a sewing machine, the combination of a machine frame having an overhanging arm, a pair of shafts carried thereby, one a rock shaft, means for driving said shafts, an oscillating arm connected to the rock shaft, a reciprocating needle bar, a link pivotally connecting said needle bar to the oscillating arm to permit either a movement at right angles to the path of reciprocation

6
of the needle bar or a swinging movement to the needle bar, and camming means carried by the other of said pair of shafts and cooperating with said needle bar for vibrating the same.

15. In a sewing machine, the combination of a machine frame having an overhanging arm, a pair of shafts carried thereby, one a rock shaft, means for driving said shafts, 10 an oscillating arm connected to the rock shaft, a reciprocating needle bar, a link pivotally connecting said needle bar to the oscillating arm to permit either a movement at right angles to the path of reciprocation 15 of the needle bar or a swinging movement to the needle bar, and camming means carried by the other of said pair of shafts and cooperating with said needle bar for vibrating the same, said camming means including centering means located intermediate the ends of the needle bar for swinging the same to space the stitches.

16. In a sewing machine having an overhanging arm, the combination of a shaft 25 carried by and extending lengthwise of said arm, means including a two to one gearing for driving said shaft, a needle carrying bar, means for reciprocating said bar, and camming means carried by said shaft and cooperating with the needle bar for vibrating the same.

17. In a sewing machine having an overhanging arm, the combination of a shaft 35 carried by and extending lengthwise of said arm, means for driving said shaft, a needle carrying bar, camming means operated by said shaft and cooperating with the needle bar for vibrating the same and comprising a triangular shaped cam carried by said shaft, a forked member cooperating with said cam and connected with the needle bar, and means for supporting the needle bar on said arm for vibratory movement.

18. In a sewing machine having an overhanging arm, the combination of a shaft 45 carried by and extending lengthwise of said arm, means for driving said shaft, a needle carrying bar, camming means operated by said shaft and cooperating with the needle bar for vibrating the same and comprising a triangular shaped cam carried by said shaft, a forked member cooperating with said cam and connected with the needle bar, and means for supporting the needle bar on

said arm for vibratory movement, said supporting means constructed to permit the needle to have vibratory movement in the arc of a circle. 55

19. In a sewing machine having an overhanging arm, a pair of shafts carried by and extending lengthwise of said arm, means for driving said shafts, a needle carrying bar, means connected with one of said shafts for reciprocating the needle bar and camming means carried by the other of said shafts and connected with the needle bar for vibrating the needle bar. 60

20. In a sewing machine having an overhanging arm, a pair of shafts carried by and extending lengthwise of said arm, means for driving said shafts, a needle carrying bar, means connected with one of said shafts for reciprocating the needle bar, camming means carried by the other of said shafts and connected with the needle bar intermediate its 75 ends for vibrating the needle bar.

21. In a sewing machine having an overhanging arm, a pair of shafts carried by and extending lengthwise of said arm, means for driving said shafts, a needle carrying bar, means connected with one of said shafts for reciprocating the needle bar and means including a changeable cam carried by the other of said shafts and connected with the needle bar intermediate its ends for vibrat- 85 ing the needle bar. 90

22. In a sewing machine having an overhanging arm, a pair of shafts carried by and extending lengthwise of said arm, means for operating said pair of shafts and including gearing partly carried by one of said pair of shafts, stitching mechanism including a needle carrying bar, means connecting said needle bar with one of said shafts for reciprocating it and including an oscillating arm and a link pivotally connecting said needle bar and arm to permit either a movement at right angles to the reciprocating path of the needle bar or a swinging movement to the needle bar and including camming means carried by said gear carrying shaft, and means also connected with the gear carrying shaft for operating the stitching mechanism to make an ornamental stitch. 95

Signed at Nyack, New York, this 27th day 105 of November, 1925.

JOHN P. WEIS.
